(57) **CLAIM**

I claim the ornamental design for a thread hanger, as shown and described.

DESCRIPTION

FIG. 1 is a top, front, and left side perspective view of a first embodiment of a thread hanger showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a top, front, and left side perspective view of a second embodiment of a thread hanger showing my new design;

FIG. 7 is a front elevational view thereof;

FIG. 8 is a right side elevational view thereof;

FIG. 9 is a top plan view thereof; and,

FIG. 10 is a bottom plan view thereof.

The broken lines disclosure are understood to indicate holes which do not form part of the claimed design, and the break line is understood to indicate that the vertical dimension is intended to be of an unclaimed length.
